UNITED STATES PATENT OFFICE.

EDWARD POOLE, OF PHILADELPHIA, PENNSYLVANIA, ASSIGNOR TO THE IVINS, DIETZ & METZGAR COMPANY, OF SAME PLACE.

DESIGN FOR CARPET.

SPECIFICATION forming part of Design No. 26,919, dated April 13, 1897.

Application filed December 26, 1896. Serial No. 617,098. Term of patent 3½ years.

To all whom it may concern:

Be it known that I, EDWARD POOLE, a subject of the Queen of Great Britain, residing at Philadelphia, county of Philadelphia, and State of Pennsylvania, have invented and produced a new and original Design for Carpet Fabrics, of which the following is a full, clear, and exact description, reference being had to the accompanying drawing, which forms a part of this specification.

My design, as shown in the drawing, consists of a new design for the body and border of a carpet fabric or rug.

The drawing represents one of the four corners of a rug.

A represents the body, and B the border.

The body consists, mainly, of a dark background, but with a lighter background adjacent to the border. At one point the lighter background extends deeply into the darker background. The lighter background is covered by a number of closely-arranged figures of different sizes, while on the darker background are a few comparatively widely sepa-

rated figures and a large closely-figured design at the inner corner adapted to match with similar designs on the other sections of the rug.

The border B is composed of several longitudinal sections, the prevailing feature of the design of the whole border being a leaf effect modified by ornamental figures of various sizes.

Having now fully described my invention, what I claim, and desire to secure by Letters Patent, is—

1. In a design for a carpet fabric, the body A substantially as shown.
2. In a design for a carpet fabric, the border B substantially as shown.
3. The design for a carpet fabric comprising the body A and the border B.

In testimony of which invention I have hereunto set my hand.

EDWARD POOLE.
